UNITED STATES PATENT OFFICE.

PETER J. MORCK, OF SAN FRANCISCO, CALIFORNIA.

BRUSH.

Application filed May 18, 1922. Serial No. 561,817.

To all whom it may concern:

Be it known that I, PETER J. MORCK, a citizen of the United States, and a resident of the city and county of San Francisco, State of California, have made a new and useful invention, to wit: Improvements in Brushes; and I do hereby declare the following to be a full, clear, concise, and exact description of the same:

10 This invention relates particularly to an improved type of painter's or kalsomine brush.

An object of the invention is to provide an improved brush, wherein the bristles are 15 fixedly embedded against dislodgement and so arranged and constructed that shrinkage or swelling of the bristles is compensated for.

20 A further object of the invention is to provide a brush having rubber gripped bristles mounted on a supporting handle so that the outer faces of the bristles will be maintained substantially parallel. Other objects and advantages will appear as this 25 description progresses.

In this specification and the annexed drawings, the invention is illustrated in the form considered to be the best, but it is to be understood that the invention is not limited 30 to such form, because it may be embodied in other forms; and it is also to be understood that in and by the claims following the description, it is desired to cover the invention in whatsoever form it may be embodied.

35 In the accompanying one sheet of drawings,

Fig. 1 represents a side elevation of a brush constructed in accordance with my invention.

40 Fig. 2 is a vertical section through Fig. 1 on the line 2—2.

Fig. 3 is a plan section view taken through Fig. 2 on the line 3—3.

In detail, the construction illustrated in 45 the drawings comprises a brush consisting of the base portion 1, having a handle member 2 thereon.

The brush element is formed of the bristles 3, having the ends thereof impregnated or treated with rubber or a similar composition. The treated ends of the bristles 3 are arranged within a suitable metal frame 4, having its inner face 5 beveled so that the thicker portion of the frame 4 extends beyond the treated portion 55 of the bristles while the inner edge of the

frame lies substantially flush with the ends of said bristles. The beveled face 5 of the frame 4 engages the bristles so as to prevent the same flaring outwardly, and maintained 60 in substantially parallel alignment with the outer face of the frame 4. The bristles 3 are arranged in rows within the interior of the frame 4 in either a longitudinal or transverse position, as illustrated by the rows 6, 65 7, 8, and 9 in Fig. 3, each of said rows being separated and spaced apart by the resilient partitions or box frames 10, 11, 12, 13 and 14 respectively. The metal partitions 10—14 are formed from a light gauge, sheet 70 metal and consist of parallel side walls 15 and 16, end walls 17 and 18 and a bottom wall 19. This manner of constructing the partitions permits them to be adapted to the shape of the rows of treated bristle ends 75 if the thickness of the same be not uniform throughout. The ends and sides of all of the partition members 10—14 are adapted to be spaced from each other and also to be spaced from the contiguous inner face of the 80 outer frame 14.

The sections of bristles and partitions are assembled within the frame 4 in the following manner. The frame 4 is placed on one of its longer sides and a row of treated 85 bristle ends laid in contact with the lower inner face of said frame and, also, in contact with the inner end faces of said frame. The partition 10 would then be laid on top of the treated bristle ends. A layer of treated 90 bristle ends 6 would then be laid on top of the partition 10 and the respective partitions and treated bristle ends superposed, one on the other, in alternate relation, so as to fill the entire interior of the frame 4.

95 As previously described, the bristle ends are treated or impregnated with rubber or similar composition. When the treated bristle ends and partitions have been arranged in the desired manner within the supporting frame 4, a pair of nails or rods 22 and 23 are passed through the frame 4, so as to engage the alternate layers of treated 100 bristles and the partitions and to hold the respective parts in a relatively immovable position. The assembly is then placed in a suitable retort so that the rubber treated or 105 impregnated ends may be vulcanized to form a hard homogeneous mass. After the vulcanizing process, the bristles are suitably 110 dried and allowed to set.

The type of brush illustrated, used in

painting operations and for other uses, is subjected more or less to moistened working conditions. The brush bristles, which are usually made from hair, straw, vegetable fiber and the like, thus, swell or expand when moistened and contract when dried. The usual method of binding the bristle ends within the brush cannot efficiently compensate for any contraction and expansion of the brush bristles due to moisture or the like, and, as a result, the same fall out or are so loose as to be pulled out when placed in the slightest contact with any article or surface. With a brush constructed after the manner of my invention, expansion and contraction are taken care of and compensated for by resilient and springy metal partitions 10—14 and which automatically move into or out of their normal configuration by the swelling or contracting action of the bristles. Drilled blocks 20 are adapted to be arranged

within the hollow partitions 6 and 14, through which wood screws or nails 21 may be passed for joining the brush part to the handle back 2 for securing the entire assembly in rigid and fixed position.

Having thus described this invention, what I claim and desire to secure by Letters Patent is:

A brush comprising a frame; a plurality of rows of bristles having vulcanized ends arranged in said frame; a plurality of resilient and hollow U-shaped in cross section partitions adapted to be positioned between the vulcanized ends of said rows of bristles; and means for securing said frame to a handle.

In testimony whereof, I have hereunto set my hand at San Francisco, California, this 9th day of May 1922.

PETER J. MORCK.
